UNITED STATES PATENT OFFICE.

JOHN BYRON DUNKIN, OF BELLINGHAM, WASHINGTON.

FRAMING-MACHINE.

1,356,490.

Specification of Letters Patent. Patented Oct. 19, 1920.

Application filed January 7, 1919. Serial No. 270,048.

To all whom it may concern:

Be it known that I, JOHN BYRON DUNKIN, a citizen of the United States, residing at Bellingham, in the county of Whatcom 5 and State of Washington, have invented new and useful Improvements in Framing-Machines, of which the following is a specification.

This invention relates to woodworking 10 machines, and aims to provide a portable machine of simple construction for cutting mortises in heavy timbers, being especially useful in the framing of ships.

Another object is to provide a device of 15 this character which may be adjustable to cut mortises, such as square or inclined mortises, the adjustment permitting of use of the device in various positions.

A further object of the invention is to 20 provide a machine of this character which is power operated, the operator or workman controlling the machine so as to cut the mortise at a proper depth or degree.

Other objects and advantages of the in- 25 vention will appear as the following de- scription is read in connection with the accompanying drawings.

Figure 1 is a side elevation showing the machine in position for use.

30 Fig. 2 is a sectional view on the line 2—2 of Fig. 1.

Fig. 3 is an enlarged detail sectional view on the line 3—3 of Fig. 2.

Fig. 4 is a plan view illustrating the ma- 35 chine in position for cutting a mortise dif- ferent from that shown in Fig. 1, and

Fig. 5 is an elevation of Fig. 4.

Referring to the drawings in detail, like 40 characters of reference denote correspond- ing parts throughout the several views.

In Fig. 1, the machine is shown as used 45 for cutting a mortise, the bottom and one end wall of which is inclined. The ma- chine comprises a cutting member 10, which is mounted upon one end of a rotary shaft 11, the latter being driven from a suitable 50 source of power through a connection 12, which is coupled to the shaft as shown at 13 and may be connected to any suitable source of power.

The cutting member 10 includes a hub 55 14 which is secured upon the shaft 11, the said hub having cutting blades 16. The blades 16 are spirally arranged and are disposed longitudinally with respect to the hub 14, so that when the hub is revolved

the blades will make a shearing cut in the timber.

The shaft 11 is mounted in a bearing 17, which is provided with an opening 18 ar- 60 ranged longitudinally thereof and through which the shaft 11 passes in a manner to permit of its free adjustment or movement therein. The bearing 17 is also provided with a transversely disposed opening 19 65 through which passes a guide shaft 20 cy- lindrical in cross section. The mounting of the bearing permits of free adjustment of the cutter longitudinally of the shaft 20 and also permits of free adjustment of the 70 shaft 11 within the bearing 17, while the manner of mounting the bearing upon the shaft 20 enables the cutter to be tilted to any desired angle.

Removably mounted upon each end of 75 the guide shaft 20 are standards 21, each comprising a bar 22 which is provided at one end with a curved extremity 23 having an opening 24 therein for the reception of the shaft 20. Mounted upon the standards 80 21 are guides 24', by means of which the said standards are secured upon the timber. These guides are movable upon the stand- 85 ards, so that the latter may be moved to regulate the distance of the shaft 20 from the base of the timber, so as to regulate the inclination of the mortise.

In Figs. 4 and 5, the machine is shown 90 applied to cut a square mortise. The struc- ture of the machine is the same as that de- scribed in connection with the preceding figures, the difference being in the manner of applying the machine to the timber. As shown in Figs. 4 and 5 the standards 22 are disposed longitudinally of the cut and upon 95 the sides thereof and are held by means of guides 24' on the timber to be cut.

The blades 16 are provided upon their outer ends with transverse cutting edges 100 25, disposed at right angles to the longi- tudinal cutting edges, so that the member 10 will act to square up the mortise.

It is believed that from the foregoing de- 105 scription and the accompanying drawings, the construction, operation and advantages of the invention will be apparent. The in- vention is susceptible of various changes in its form, proportions and minor details of construction and the right is herein re- served to make such changes as properly fall 110 within the scope of the appended claims.

Having described the invention, what is claimed is:

1. A mortising machine comprising a supporting frame including spaced parallel side members and a transverse bar, connecting said members, means for securing the frame in position, a bearing mounted upon the transverse bar and capable of both pivotal movement and movement longitudinally of the bar, a shaft rotatably and longitudinally movable in said bearing and a cutting member carried by the shaft.
2. A mortising machine comprising a supporting frame including spaced parallel

side members and a transverse bar connecting said members, means for securing the frame in position, a bearing member having a shaft receiving opening therein and an opening disposed transversely of the shaft receiving opening for slidably and pivotally receiving the transverse bar, a shaft positioned in the shaft receiving opening and capable of rotary and longitudinal movement therein and a cutting member carried by the shaft.

15

In testimony whereof I affix my signature.

JOHN BYRON DUNKIN.
